Nelson W. Howard

UNITED STATES PATENT OFFICE

FRED L. MOONEY, OF LYNN, MASSACHUSETTS, ASSIGNOR TO UNITED SHOE MACHINERY CORPORATION, OF PATERSON, NEW JERSEY, A CORPORATION OF NEW JERSEY

METHOD OF AND APPARATUS FOR LOCATING ELEMENTS UPON SHOE BOTTOMS

Application filed July 10, 1929. Serial No. 377,166.

My invention relates to the positioning of such elements as the stiffening or reinforcing pieces for the shank-portions of shoes upon the bottoms of said shoes, it involving both a method for attaining the desired position and an apparatus by which said method may be carried out.

To obtain the proper reinforcing effect for a shank-piece without interfering with the flexibility of the forepart of the shoe or impairing the appearance of the outsole, it is necessary that the reinforcement shall be placed with considerable accuracy. The location of its forward extremity is of particular consequence in connection with the leveling of the outsole. To permit this to be done without deformation of the exposed surface of the outsole, the end of the reinforcement should lie substantially at the ball-line, or where the forepart of the shoe merges into the shank-portion in a reverse curve. If the reinforcement extends beyond the ball-line, there is a tendency to produce an unsightly projection in the outsole when this is leveled, and the reinforcement may also penetrate the outsole in the wear of the shoe. With the end of the reinforcement at the rear of the ball-line, leveling may cause a depression in the outsole. An object of my invention is to locate quickly, and with the desired exactness, shank-reinforcements upon the bottoms of shoes, regardless of the style and size of the shoes.

In the attainment of the above object, a feature of the invention may be found in a method which, as herein exemplified, consists in bringing together a shoe-bottom and a gaging member to form a recess between them, and inserting an end of a shank-reinforcement or other element in the recess to locate it. By establishing this gaging contact over the forepart of the shoe-bottom with an overhang of the member at the shank-portion, the locating recess is formed at the ball-line, so not only is the relation sought obtained, but this will be unvarying as the style and size of the shoes change. The operator is therefore relieved of thought, other than for the mere performance of a routine manipulation. When the

shank-reinforcement is under the influence of the gaging member, the operator may secure it to the shoe-bottom, avoiding danger of displacement.

A further feature of the invention resides in a locating apparatus for the performance of the above method. In this there is a shoe-support and a gage member, with which is combined means arranged to move them relatively, these elements preferably also having a relative movement of self-adjustment, the gage member being illustrated as pivoted upon a movable carrier. The two relative movements bring the gage member into contact with the bottom of a shoe on the support, as over the forepart, and, as the member and shoe-bottom come together, they assume the same inclination, the former accommodating itself to the latter. Thus there is automatically located the breast-line where the shank-portion falls away, and the previously mentioned gaging recess is produced, whatever the character of the shoe operated upon. Since the forward ends of different types of shank-pieces may be of diverse forms, the member preferably has a plurality of gaging surfaces, which may be made selectively available for use according to the particular reinforcing means employed. Sometimes the reinforcement is secured to the shoe by such devices as prongs integral with said reinforcement and adapted to be driven into the bottom. This attachment I conveniently accomplish by a driving member, herein illustrated as a reciprocatory driver-bar co-operating with the gaging member. The driving member may be actuated by the operator, as the result of a hammer-blow, to insert the prongs of the reinforcement located by the gage member. The shoe-support is preferably provided by a jack-post movable into and out of operating position and a jack-top movable upon the post. Co-operating with the jack-post, I have shown a stop to determine the operating position of the jacked shoe, this stop having a surface arranged for engagement with the maximum inwardly curved portion of the upper at the instep. The combined movement of the post

and top enables the operator to readily effect contact of the shoe with the stop at the chosen point, and thus position it to receive the action of the gage member.

5 A particular embodiment of the apparatus of this invention and a modification thereof appear in the accompanying drawing,

Fig. 1 being a perspective view of the entire apparatus, with parts broken away;

10 Fig. 2, a side elevation of the gage-head in co-operation with a shoe and shank-reinforcement; and

15 Fig. 3, a view similar to Fig. 2, but illustrating another form of gage member.

20 A frame 10 may carry a table 12, arranged to hold the shank-reinforcements to be applied, the securing tacks and the operator's hammer or other tools. Pivoted upon a bracket 14 projecting from the front of the 25 frame below the table is a jack-post 16 extending in a generally vertical direction above the table and having at its upper extremity a pivoted top 18. Rising from this top is a pin 20 adapted to enter a hole in the 30 cone of a last, as illustrated at L. This last has upon it a shoe-upper S with an insole I ready for the application of a shank-reinforcement. Both the jack-post and top are shown as having means for temporarily 35 retaining them in whatever positions they may be placed. This, in each instance, may consist of a frictional device including a plunger 22 movable, respectively, in bores in the bracket and post, and urged by a spring 24 against the element to be retained.

40 Secured to the table 12, at the rear of the jack-post, is a standard 26, to which is fulcrumed a carrier-lever 28 forked at its forward extremity to receive a head 30 arranged to oscillate through a limited angle and to be further varied in its angular relation about a horizontal pin 32 extending between the arms of the lever-fork. A pin 34, passing through one of the arms of the lever 45 and threaded into the other, may traverse any one of three arcuate openings 36 in the head. Each opening is sufficiently long to give the head an oscillating movement of self-adjustment about its pin 32, limited in extent by contact between the pin 34 and the ends of the openings 36. Removal of the limiting pin allows the head to be positioned angularly to place in active position any one of three operating faces *a*, *b* and *c*. 50 Each of these faces has a projection 38 arranged for contact with the insole I just forward of the breastline, a projection 40, spaced along the insole from 38 toward the toe of the shoe, and a gaging surface 42 extending rearwardly from the projection 38. The face *a* is arranged, in Figs. 1 and 2, in operating position. It, or either of the other faces selected and turned into the gaging relation, is lowered into co-operation 55 with a jacked shoe by a treadle 44 pivoted

at the bottom of the frame, and a connecting rod 46 articulated to the lever 28 and joined to the treadle by a spring 48. This spring causes the movement of the treadle to be yieldably communicated to the head. A spring 50 holds the treadle and head normally elevated, so the latter is raised above the jack.

60 The gaging face *a* is utilized to locate such a reinforcing piece as appears at M (Fig. 2). This is of metal, and has at its forward end, next to the insole of the shoe receiving it, curved securing prongs *m*, which are to be driven into the insole. In using the apparatus and carrying out my method in connection with this reinforcement, the operator, with the jack-post 16 drawn out, applies to its pin 20 a lasted shoe-upper S with its insole I, and swings in the post, at the same time tilting the top 18 upon it as is necessary to bring the incurved portion of the instep against a stop 49. This stop I have shown as in the form of a cylinder having its axis extending horizontally and mounted upon a shank 51 threaded into a rearwardly extending portion of the standard 26. This mounting permits the vertical position of the stop to be initially determined, after which it is locked by a nut 53 upon the shank. The contact of the work with the stop 49, as just described, is sufficiently accurate to so locate the forepart of the shoe that the projections 38 and 40 will contact properly with it for all sizes, the gaging surface 42 extending from the 100

forepart rearwardly over the shank-portion, and forming therewith a gaging throat to receive the forward end of the reinforcement. The treadle 44 is now depressed, bringing down the head 30. The projection 40 of the face *a* engages the forepart of the insole at some point forward of the ball-line, while the projection 38 contacts therewith adjacent to the ball-line, the gaging surface 42 overhanging the shank-portion and converging forwardly to the ball-line. The operator then inserts the shank-reinforcement in this gaging recess, seating it at its forward extremity in the apex of the throat, and positioning it transversely by 110 his eye, the accuracy of the latter relation not being important. The contact of the gage-projections with the insole at separated points, rather than over a continuous surface, avoids a disturbance of the proper angular relation of the gaging member due to irregularities in the surface of the insole.

115 To attach this type of reinforcement M to the insole after being thus located, the head 30 is shown as having, mounted to reciprocate in a passage through it, a driver-bar 52, the lower extremity of which is held normally above the surface 42 of the face *a* by a spring 54 connecting the bar to the head. The opposite end of the bar is pro-

130

vided with an enlargement 56 adapted to receive a blow from a hammer. While the shank-reinforcement is still positioned by the surface 42, the operator thus actuates the bar to force its lower extremity against the curved forward end of the reinforcement, driving the prongs into the insole and securing this portion of the reinforcement. The prongs at the other end may be then driven into the insole by a blow of the hammer directly over them, and the locating and attaching of the reinforcement is completed. The treadle is thereupon released, the head rises, and, upon swinging out the jack and removing the lasted shoe, the apparatus is ready for again carrying out the method.

If a fiber-reinforcement N, illustrated in Fig. 3, is to be applied, the face b of the head 30 is brought into action by removing the pin 34, turning the proper opening 36 into alignment, and replacing the pin. The locating effect is generally as before, but, as the device N lacks the protuberance produced by the prongs, the surface 42 of the face b is not recessed or set back from the projection 38, but is a continuation of its contact-surface. The gaging relation for this face b is best illustrated in Fig. 3, which shows a single gaging member 58 pivoted upon the arm 28 and having its contact-projections and gaging surface arranged similarly to the face b. Such an arrangement may be employed where the apparatus is to be used in connection with a single type of shank-reinforcement. When reinforcements such as N, which are without the securing prongs of the reinforcement M, are to be attached, they have driven through the extremity opposite that by which they are located, a tack T. The forward end may be secured after the jack has been swung out. In connection with any of the shanks, pitch or other heavy adhesive may be employed as the sole or as an auxiliary securing means.

It should be particularly noted that, by locating the ball-line of a shoe-bottom by the herein disclosed method and by the employment of my improved apparatus with its tilting, self-adjusting gage member, a gaging effect is produced which determines the point of application of shank-pieces for all contours and dimensions of shoe-bottoms, there being required only the most simple, speedily-performed operations.

Having described my invention, what I claim as new and desire to secure by Letters Patent of the United States is:

1. The method of locating elements upon shoe-bottoms, which consists in bringing together a shoe-bottom and a gaging member to form a recess, and inserting an end of an element in the recess to locate it.

2. The method of locating shank-rein-

forcements upon shoe-bottoms, which consists in bringing together a shoe-bottom and a gaging member to form a recess between them, inserting an end of a shank-reinforcement in the recess to locate it, and securing the reinforcement to the shoe-bottom while it is under the influence of the gaging member.

3. The method of locating shank-reinforcements upon shoe-bottoms, which consists in applying a gaging member to the forepart of a shoe-bottom to overhang the shank-portion, and inserting a shank-reinforcement beneath the overhang to an extent determined by the convergence of the bottom and member.

4. The method of locating shank-reinforcements upon shoe-bottoms, which consists in applying a member to the forepart of a shoe-bottom, said member extending rearwardly over the shank-portion, and placing a shank-reinforcement upon the shoe-bottom with its forward extremity in contact with the member.

5. The method of locating shank-reinforcements upon shoe-bottoms, which consists in applying a member to the forepart of a shoe-bottom, said member extending rearwardly over the shank-portion, placing a shank-reinforcement upon the shoe-bottom with its forward extremity in contact with the member, and securing the reinforcement to the shoe-bottom while it is in contact with the member.

6. In an apparatus for locating elements upon shoe-bottoms, a shoe-support, a gage member, and means arranged to move the support and gage member relatively to bring said gage member and the bottom of a supported shoe into contact, the support and gage member also having a relative movement of self-adjustment.

7. In an apparatus for locating shank-reinforcements, a shoe-support, a gage member, and means arranged to move the support and gage member relatively to bring the latter into contact with the forepart of the bottom of a shoe on the support.

8. In an apparatus for locating shank-reinforcements, a shoe-support, a carrier, a gage member mounted for self-adjustment upon the carrier, and means arranged to move the support and carrier relatively to bring the gage member into contact with the forepart of the bottom of a shoe on the support.

9. In an apparatus for locating shank-reinforcements, a shoe-support, a carrier, a member mounted for self-adjustment upon the carrier and provided with a plurality of gaging faces any one of which is selectively available for use, and means arranged to move the support and carrier relatively to bring the selected face into contact with the

- forepart of the bottom of a shoe on the support.
10. In an apparatus for locating shank-reinforcements, a shoe-support, a carrier, a gage member mounted for self-adjustment upon the carrier and having contact-portions spaced from one another, and means arranged to move the support and carrier relatively to bring the contact-portions of the gage member against the forepart of the bottom of a shoe on the support.
11. In an apparatus for locating shank-reinforcements, a shoe-support, a carrier, a gage member mounted upon the carrier and having contact-portions spaced from one another, one of the contact-portions having an extended gaging surface, and means arranged to move the support and carrier relatively to bring the contact-portions of the gage member against the forepart of the bottom of a shoe on the support with the gaging surface extending rearwardly over the shank-portion of said shoe.
12. In an apparatus for locating shank-reinforcements, a shoe-support, a carrier, a gage member mounted upon the carrier, a driving member co-operating with the gage member, and means arranged to move the support and carrier relatively to bring the gage member into contact with the forepart of the bottom of a shoe on the support.
13. In an apparatus for locating shank-reinforcements, a frame, a support mounted thereon, a carrier movable upon the frame, a gage member pivoted to oscillate upon the carrier, and means arranged to move the carrier and bring the gage member against the bottom of a shoe on the support.
14. In an apparatus for locating shank-reinforcements, a frame, a support mounted thereon, a carrier movable upon the frame, a gage member pivoted to oscillate upon the carrier and having spaced contact-projections from one of which extends a gaging surface, and means arranged to move the carrier and bring the contact-projections of the gage member against the forepart of a shoe on the support.
15. In an apparatus for locating shank-reinforcements, a frame, a support mounted thereon, a carrier movable upon the frame, a gage member pivoted to oscillate upon the carrier, a driver movable upon the gage member, and means arranged to move the carrier and bring the gage member against the forepart of a shoe on the support.
16. In an apparatus for locating shank-reinforcements, a frame, a jack-post movable thereon into and out of operating position, a jack-top movable upon the post, and a gage member movable upon the frame into and out of engagement with the forepart of the bottom of a jacked shoe.
17. In an apparatus for locating shank-reinforcements, a frame, a jack-post mov-

able thereon into and out of operating position, a jack-top movable upon the post, means for frictionally retaining the post and top in the position to which they are moved, and a gage member movable upon the frame into and out of engagement with the forepart of the bottom of a jacked shoe.

18. In an apparatus for locating shank-reinforcements, a frame, a jack-post movable thereon into and out of operating position, a jack-top movable upon the post, a stop arranged to determine the position of the jacked shoe, and a gage member movable upon the frame into and out of engagement with the bottom of a jacked shoe.

19. In an apparatus for locating shank-reinforcements, a frame, a jack-post movable thereon into and out of operating position, a jack-top movable upon the post, a stop fixed upon the frame and having a surface arranged for engagement with the upper of a jacked shoe at the maximum inwardly curved portion of the instep, and a gage member movable upon the frame into and out of engagement with the forepart of the bottom of a jacked shoe.

20. In an apparatus for locating shank-reinforcements, a frame, a lever fulcrumed thereon, a gage member carried by the lever, a jack-post supported upon the frame, and connections to the lever arranged to move the gage member into contact with the bottom of a jacked shoe.

21. In an apparatus for locating shank-reinforcements, a frame, a lever fulcrumed thereon, a gage member pivoted upon the lever, a jack-post pivoted upon the frame below the lever, and connections to the lever arranged to move the gage member into contact with the bottom of a jacked shoe.

22. In an apparatus for locating shank-reinforcements, a frame, a lever fulcrumed thereon, a gage member carried by the lever, a jack-post movable upon the frame, a treadle, and yieldable connections between the treadle and lever.

23. In an apparatus for locating shank-reinforcements, a frame, a lever fulcrumed thereon, a gage member carried by the lever, a jack-post supported upon the frame, a driver associated with the gage member, and connections to the lever arranged to move the gage member into contact with the bottom of a jacked shoe.

24. In an apparatus for locating shank-reinforcements, a frame, a carrier movable thereon, a head mounted to turn upon the carrier and having on its periphery a plurality of gaging faces respectively arranged for co-operation with different forms of shank-reinforcement, and a jack-post supported upon the frame and arranged to present a shoe to the head.

25. In an apparatus for locating shank-reinforcements, a frame, a lever fulcrumed

thereon, a head mounted to turn upon the lever and having on its periphery a plurality of gaging faces respectively arranged for co-operation with different forms of shank-reinforcement, a driver-bar movable upon the head, and a jack-post supported upon the frame and arranged to present a shoe to the head.

26. In an apparatus for locating shank-reinforcements, a frame, a lever fulcrumed thereon, a head mounted to turn upon the lever and having on its periphery a plurality of gaging faces respectively arranged for co-operation with different forms of shank-reinforcement, a driver-bar mounted for reciprocation upon the head with its work-engaging end adjacent to one of the gaging surfaces, and a jack-post supported upon the frame and arranged to present a shoe to the head.

20 In testimony whereof I have signed my name to this specification.

FRED L. MOONEY.
